UNITED STATES PATENT OFFICE

FREDRICK N. YOUNG, OF CLAREMONT, NEW HAMPSHIRE

STAPLE AND NAIL EXTRACTOR

Application filed October 2, 1926. Serial No. 139,199.

The present invention pertains to a novel staple and nail extractor constructed in a simple manner and adapted to accomplish its expected functions as effectively as possible.

The device comprises essentially a housing in which are supported a fixed jaw and a movable jaw. The movable jaw is formed with a cam face or similar arrangement adapted to be engaged by a handle which is also pivoted in the housing. The jaws when opened are placed at opposite sides of the nail or staple, and the handle is then swung on its pivot so that the movable jaw closes against the fixed jaw whereby the nail or staple is grasped between the two jaws. Continued pressure on the handle causes the entire device to swing about a heel or a bearing piece carried thereby whereupon the nail or staple is extracted.

The invention comprises further a hammer sleeve slidably mounted on the free end of the handle so that the points of the jaws may be driven into the wood to grasp an embedded staple or nail head which cannot otherwise be reached.

The invention is fully disclosed in the following description and in the accompanying drawings in which:

Figure 1 is a perspective view of the staple extractor;

Figure 2 is a plan view thereof in closed position;

Figure 3 is a plan view thereof in grasping position;

Figure 4 is a side elevation of the extractor applied to a staple;

Figure 5 is a sectional view of the handle;

Figure 6 is a perspective view of a nail puller;

Figure 7 is a plan view thereof with one of the plates removed;

Figure 8 is a section on the line 8—8 of Figure 7; and

Figure 9 is a front elevation of the nail extractor.

Reference to these views will now be made by use of like characters which are employed to designate corresponding parts throughout.

The staple extractor shown in Figures 1 to 5 inclusive comprises a hollow housing 1 having a bearing piece or heel 2 projecting from the forward side thereof. Within the housing, near the upper wall thereof, is secured a stationary jaw 3 and a pivoted jaw 4. The jaws are opposed to one another and held to the top of the housing by screws 5, the stationary jaw being further maintained by a pin 6 which prevents turning. The shank of the swinging jaw 4 is formed with a recess adapted to provide an arcuate cam 7 as clearly shown in Figures 2 and 3. Through the rear wall of the housing is passed a handle 8 which is fastened therein by a pivot pin 9 on which it is adapted to turn. The inner end of the handle is formed with an angular upwardly directed projection 10 formed with a bevelled head designed to engage the cam formed on the swinging jaw 4 and forcibly swing the jaw to closed staple engaging position. The projection 10 is accommodated in a notch 11 cut in the upper wall of the housing. The handle 8 is maintained in a central position with respect to the pin 9 by means of spacing rings 12 surrounding the pin at both sides of the handle.

The handle 8 is surrounded by a heel 13 which is used as a hammer for driving the points of the jaws 3 and 4 into the wood when the staple is embedded therein too far to be reached otherwise. In such a case the heel 13 is drawn outwardly with respect to the handle 8 and then driven forcibly against the handle after the claws have been placed at opposite sides of the staple. The end of the handle is cushioned as at 14 and is also equipped with a ring 15 held by a pin 16 passed through both the handle and the ring. The forward end of the heel has a collar 17 threaded therein.

and adapted to slide loosely on the handle. This collar in conjunction with the ring 15 prevents the heel from being pulled off the handle.

The use of the device is illustrated more clearly in Figure 4 in which is illustrated a post 18 having a staple 19 driven therein. The claws are placed at opposite sides of the staple in such a manner that the handle 8 assumes substantially a horizontal position.

10 The points of the jaws 3 and 4 are driven into the wood if necessary and the handle 8 is then lowered whereupon the point 10 riding against the cam face 7 causes the movable jaw 4 to swing towards the fixed jaw 3 whereby 15 the staple is grasped between the two jaws. The downward pressure of the handle 8 is continued whereby the entire device is caused to swing about the heel 2 as a pivot so that the staple is withdrawn.

20 The same construction as modified for a nail puller is illustrated in Figures 6 to 9 inclusive. The housing for this device comprises a pair of plates 20 and 21 secured together by screws 22 and having internal 25 flanges 23 so that an interior cavity is formed for accommodating the working parts. A fixed jaw 24 and a swinging jaw 25 project through the forward end of this housing and are maintained in position by bolts 26 which 30 further serve to support a bearing piece 27. The fixed jaw 24 is further held by a pin 28 passed through the plates 20 and 21 in order to prevent turning. The shank 29 of the swinging jaw 25 has in its outer edge a notch 30 which receives one end of a flat spring 31 secured to one of the flanges 23. This spring tends to move the inner end of the jaw 25 towards the fixed jaw 24 and thereby to separate the points of the two jaws. The inner 35 edge of the swinging jaw is formed with a recess 32 for receiving a lug 34 on the inner end of a handle 33 pivotally supported between the plates 20 and 21 by a pin 35. The operation of this device is substantially similar to that previously described except that in this instance the handle swings in the plane of the jaw rather than in a plane perpendicular thereto.

40 While a specific embodiment of the invention has been illustrated and described, it is to be understood that various alterations in the details of construction may be made without departing from the spirit of the invention 45 as indicated by the appended claim.

Having thus fully described the invention, what I claim as new and desire to protect by Letters Patent is:—

49 An extractor comprising a housing, a fixed 50 jaw secured in the housing and having its outer engaging end projecting longitudinally from one end of the housing, a pivoted jaw mounted in opposed position to the fixed jaw and adapted to adjustably co-act therewith, 55 and a handle arranged rearwardly of and con-

tiguously with said movable jaw and extending longitudinally from the opposite end of the housing, said handle being pivoted to said housing for swinging movement in a plane at right angles to the swinging movement of the pivoted jaw and formed with an angular projection engageable with the inner end of the pivoted jaw to actuate the jaw to article engaging position.

70 In witness whereof I have hereunto set my hand.
